(57) **CLAIM**

The ornamental design for a insect hood for a horse, as shown and described.

DESCRIPTION

FIG. 1 is a top, front, right perspective view of an insect hood for a horse, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The drawings are shaded to indicate contrasting surfaces; the crosshatched surfaces depict an open-mesh textile.

In the drawings, the equal-length broken lines depict portions of the insect hood for a horse that form no part of the claimed design. The dash-dot-dash broken lines define the boundaries of the claim and form no part of the claimed design.
